FLUSH TANK BALL VALVE

Charles H. Rennels, near Poland, Ohio
(509 Laird Ave., Poland, Ohio)

Filed Feb. 19, 1963, Ser. No. 73,627

Term of patent 14 years

(Cl. D91—1)

FIGURE 1 is a perspective view of a flush tank ball valve, showing my new design;

FIGURE 2 is a perspective view of a modified form of the flush tank ball valve;

FIGURE 3 is a bottom plan view, on a reduced scale, of the form of the invention seen in FIGURE 2.

The sides not shown in FIGURES 1 and 2 are the same as the sides shown. The portion shown in broken lines in FIGURES 1 and 2 is included for illustrative purposes only.

I claim:

The ornamental design for a flush tank ball valve, as shown and described.
